A CORPORATION OF WEST VIRGINIA

METHOD OF AND APPARATUS FOR TREATING ORES

Application filed January 15, 1927. Serial No. 161,286.

It has been found desirable to film certain crushed ores with acetylene during grinding and preparatory to froth flotation. By filming with acetylene is meant bringing mineral particles to a condition in which they are amenable to flotation. In case of copper ores, for example, the so-called oxidized ores, including carbonates and silicates, require filming. These have been floatable when thus treated with acetylene. While various ways have been suggested and tried for this treatment, the most efficient and practical method has been found to be the treatment of the ore with gas during the process of wet grinding.

A common form of wet grinding mill is the conical ball mill frequently arranged in closed circuit with a classifier, in which the discharge of the grinding mill is separated into a finished product, accompanied by a relatively large quantity of water, discharged by overflowing at one end of the classifier, and into a sandy or coarse product, accompanied by a relatively small amount of water, discharged at the opposite end of the classifier, the coarse or oversize product being returned to the mill for further reduction in size. If the ore be treated with gaseous acetylene in the conventional installation wherein the mill is not gas-tight, such treatment would be too expensive because of leakage of the acetylene and hazardous because acetylene mixed with air is highly explosive.

It was suggested that the wet grinding might be done in batches in a closed mill, but while this might be practical for the laboratory, grinding in batches is impracticable in the field because of the complications and consequent expense of introducing intermittent operations into what are otherwise continuous. Any means for reducing the cost and hazard of using acetylene must be simple, cheap and adapted for use with existing methods and apparatus. Experimental work disclosed that the oversize material to be returned to the grinding mill from the classifier would clog or choke in any form of pipe or conduit connecting the two and adapted to maintain the mill gas-tight, as for example a U seal. A sump and pump were suggested but the abrasive character of the ma-

terials and the small percentage of water allowable rendered this apparatus impractical. If water were added to make a freely flowing material capable of being pumped several objections would result. Excess water means excess absorption of acetylene by the water and, therefore, unnecessary expense in gas required, and additional means for separating the water from the ore to be ground would be required. Also the grinding capacity of the mill is greatly reduced when too much water is present, and if the mill is flooded the filming operation will not be as satisfactory as when gas can more readily contact with the ore, so that a small amount of water is desirable, the amount depending on the type of ore and other practical considerations, the customary density in the grinding mill varying from about 50% of water to ore down to about 30% of water to 70% ore. Another difficulty has been in the necessity of feeding the material at varying rates as supplied from the classifier. Also with ball mills in continuous operation the device must allow the introduction of new balls to replace those worn out, without breaking the seal and allowing air to enter the mill or gas to escape.

The art remained in this situation for some time, the advantages of filming with acetylene were realized but because of the practical difficulty of making the operation economical and safe it was suggested that the application of filming with acetylene to the existing practice in mills be dropped. Under this invention these difficulties have been overcome and a simple, safe, inexpensive means devised which is adaptable to existing apparatus.

According to this invention, the feeding of wet crushed ore into a substantially gas-tight enclosure is accomplished by shortening the feed passage because of the clogging tendency and then making use of the clogging character of the material to form a substantially gas-tight moving plug, the feed being supplied and compacted behind the plug as the same is advanced into the enclosure. Specifically the means for doing this is located between discharge end of a classifier and an

enclosing casing around the usual scoop on the feed end of a ball mill and comprises some means such as a feed screw capable of exerting pressure upon a gas-tight plug of this material formed in a short passage between the end of the screw and the gas-tight enclosure, the mill being made gas-tight around its bearings, etc. and the discharge of the mill being arranged to take place below the water level in the classifier. To conserve acetylene, the overflow of the classifier may be subjected to a vacuum or any other separating treatment by which the absorbed gas or a portion or all of the accompanying water may be removed from the ore and returned to the grinding mill for use over again.

Referring to the drawings:—

Fig. 1 is a plan view of the invention applied to a ball mill and classifier in closed circuit;

Fig. 2 is a right hand view partly in section of the device in Fig. 1;

Fig. 3 is a right end view partly in section of the device in Fig. 1; and

Fig. 4 shows a modified construction of the discharge from the screw feed.

Fig. 5 is a modified construction with the feed screw arranged at an angle.

Fig. 6 is another construction with the feed screw vertically disposed.

For purposes of illustration, the invention is shown in connection with a conical ball mill 10 in closed circuit with an inclined type classifier 11 as is common. For the sake of clearness, the mechanism for moving the material up the incline in the classifier has not been shown. The feed end of the mill is provided with a gas-tight casing 12 in which is located a conventional feed scoop 13. A feed screw 14 pushes the wet crushed material into the casing 12. A hopper 15 located above the feed screw receives the coarse material discharged at the upper end of the classifier. Material is supplied to this closed circuit preferably to the portion that is not gas-tight, as for example into the hopper 15 from the chute 29, receiving the material to be ground, from a crusher. The discharge from the mill is through the pipe 16 extending to below water level in the classifier. As illustrated, a convenient manner of attaching the discharge pipe 16, is a sheet metal housing 17 secured to one bearing and extended around the discharge from the mill, the pipe 16 being fixed to the end of the housing 17 by a gas-tight connection.

The water and fine material overflowing from the classifier may be passed through a pipe 32, a thickener 33 or other separator and the excess water in whole or in part is preferably returned through a pump 34 and the pipes 18, 19, 20 and 21 for use again in the mill 10 for adding sufficient water to the ore at the entrance of passage 25 to submerge the

ore and form the gas-tight plug, for conveying the crushed ore to the classifier through the pipe 16, and for adding water for other purposes where gas-charged water may be advantageously utilized. It is evident that this water contains a quantity of acetylene which has been absorbed and that the use of gas-charged water reduces the gas absorption which would otherwise occur if water not containing absorbed gas were used. Water is preferably supplied through the pipe 19, the hopper 15 and the screw 14 or through the pipe 20 to the housing 12 because enough water may not enter with the feed, and again through the pipe 21 at the discharge end of the mill to prevent the discharged material clogging in the pipe 16 and at the same time furnish the necessary dilution of the pulp as required for the proper operation of the classifier. A pipe 22 supplies fresh water at the beginning of the operation, and the valves indicated enable this to be cut off and the water containing absorbed gas to be used later. Instead of rerunning the water separated from the finely ground finished product, all or a portion of it may be passed through the vacuum apparatus 23 in a spray or over the customary baffles so that the acetylene may be drawn off through the pipe 35, compressed and returned through the pipe 24 for use in the mill. The acetylene is preferably supplied from the pipe 24 to the casing 12, the portion of the circuit between the feed screw 14 and the end of the discharge pipe 16 being substantially gas-tight. This may require that all bolts and packing be carefully gone over to make the entire mill and casing substantially gas-tight. Instead of supplying acetylene in gaseous form, it may be generated within the apparatus by feeding calcium carbide into the grinding chamber or enclosure as for example, with crushed ore, through the hopper 15, but other suitable gas-tight supply means may be used for introducing the carbide. The use of carbide has an advantage over the introduction of gaseous acetylene in that the calcium hydroxide formed facilitates filming. This hydroxide or some other alkaline substance may be introduced with the ore to insure filming in the presence of alkaline material.

The feed screw 14, in the embodiment illustrated, is not provided with any bearing at the end adjacent the casing 12. A short substantially straight passage is left between the end of the screw 14 and the casing 12. It has been found that the tendency of the wet crushed ore to set or clog in this short straight passage is sufficient to form a substantially gas-tight plug between the screw 14 and casing 12 within the passage 25. In Fig. 4, a modified construction is shown for the passage 25, in which a tapered constriction 26 is placed in this passage for the purpose of offering a little more resistance to the move-

ment of material and increasing the tendency of the ore to compact and clog if its natural tendency in this regard is not sufficient. With some materials, it has been found that the tendency to pack and clog is so pronounced that an agitator 27 is needed to loosen the material just before it contacts with the rotary scoop 13. In case of necessity, a manhole 31 is provided in the casing 12 adjacent the discharge from the passage 25. In starting the apparatus the air contained within the mill and casing may be partially withdrawn through the pipe 28, or a diluent such as nitrogen may be supplied to reduce the hazard of oxygen present.

With the feed screw arranged at an angle as in Fig. 5, it has been found that a more effective and gas-tight plug is formed with some ores. Preferably the plug seal and other details are similar to those previously mentioned. The constriction of Fig. 4 may be used with the feed passages arranged as in Figs. 5 and 6. The vertical position for the feed screw in Fig. 6 illustrates another embodiment of this invention, the other details being as described in connection with Figs. 1 to 3.

Among the advantages of this invention may be enumerated its simplicity, cheapness, and adaptability for use with existing types of apparatus, particularly to grinding mills. The use of the feed screw permits additional balls to be fed in with the material from the hopper 15 to replace balls within the mill which have worn out. The use of the relatively short, substantially straight, passage 25 is effective in combatting the clogging tendency of the material and yet this tendency is present to an extent sufficient to form the material into a substantially gas-tight plug fitting with said passage. Another advantage of this invention is that it is adapted to meet the needs of the irregular rates of feed experienced in the field for it will be seen from Figs. 3, 5 and 6 of the drawings that even though the feed from the screw 14 be greatly reduced, the plug is still maintained within the passage 25.

Nothing has been said about the exact size of feed material or precise amount of water to be supplied because these features have been found to be widely variable with the different types of ores treated. Of course, if the material from the crusher is too coarse, it will not be effective in forming the plug desired in the passage 25, but experience will soon show how small the material should be. That crushed to sizes of one-half inch has been found generally suitable, although larger sizes may, with some ores, be permissible, if the coarse material of the classifier suffices to maintain an effective gas-tight plug.

What is claimed is:

1. The method of feeding crushed wet ore into a substantially gas-tight enclosure,

which comprises forming the ore into a substantially gas-tight plug, pushing the plug into the enclosure, feeding said wet ore behind the plug, and compacting the feed to maintain the plug as the same is advanced.

70

2. The method of feeding crushed wet copper ore containing oxidized copper minerals into a gas-tight enclosure, which comprises compacting the ore beneath a liquid seal into a substantially gas-tight plug within a short passage, feeding the ore behind the plug, compacting the feed while building onto said plug, and pushing the same through said passage.

75

3. The method of feeding copper ore containing carbonate copper minerals into a gas-tight enclosure, which comprises supplying water to the crushed ore, compacting the wet ore into a short gas-tight plug, feeding the wet ore behind said plug, compacting the feed while building onto said plug, and pushing the plug into said enclosure.

80

4. The method of filming ore with acetylene which comprises grinding said ore in a substantially gas-tight enclosure in the presence of acetylene, while feeding said ore into said enclosure in such manner as to preclude substantial leakage of acetylene from or of oxygen into said enclosure.

85

5. The continuous method of filming oxidized copper ore that comprises feeding such ore into a substantially gas-tight grinding chamber in such manner as to preclude substantial leakage of oxygen into said chamber or gas therefrom; grinding such ore in said chamber in the presence of acetylene and continuously discharging ground ore from said chamber in such manner as to preclude substantial leakage of oxygen into said chamber or of gas therefrom.

90

6. The method of filming crushed wet ore with acetylene which comprises forming the ore into a substantially gas-tight plug, pushing the plug into a substantially gas-tight enclosure, supplying calcium carbide to the enclosure, feeding ore behind said plug as the same is advanced, supplying water to the enclosure, grinding the carbide and wet ore within said enclosure, and discharging the ground filmed ore below the surface of a liquid seal.

95

7. The method of filming crushed ore with acetylene which comprises forming the ore into a substantially gas-tight plug, pushing the plug into a substantially gas-tight enclosure, feeding ore behind the plug, compacting the feed to maintain the plug as the same is advanced, wetting the ore, grinding the wet ore within said gas-tight enclosure in the presence of acetylene, and discharging the ground filmed ore below the surface of a liquid seal.

100

8. The method of filming crushed wet ore with acetylene in a substantially gas-tight grinding mill, which comprises supplying

105

110

115

120

125

130

- water to the mill, separating the water from solid particles in the mill discharge, and recycling at least a portion of the separated water charged with acetylene through the mill.
9. The method of filming crushed wet ore with acetylene in a substantially gas-tight grinding mill, which comprises supplying water to the mill, separating the water from some of the solid particles in the mill discharge, and withdrawing the absorbed acetylene from at least a portion of the separated water under reduced pressure.
10. The method of filming crushed wet ore with acetylene in a substantially gas-tight grinding mill, which comprises supplying water to the mill, separating water from solid particles in the mill discharge, withdrawing absorbed acetylene from at least a portion of the separated water under reduced pressure, compressing the acetylene, and recycling the same through the mill.
11. The combination with a substantially gas-tight enclosure, of means for feeding crushed ore into said enclosure, which comprises a short substantially straight passage leading into the enclosure, means for wetting the ore before entering said passage, means for compacting the wet ore to form a substantially gas-tight plug within said passage, means for pushing the plug through the passage into the enclosure, means for feeding ores behind said plug, and means for compacting the feed to build onto and maintain the plug as the material is moved through said passage.
12. The combination with a substantially gas-tight grinding mill, of means for feeding crushed ore into said mill while maintaining the mill gas-tight, means for supplying water to said mill, means for maintaining acetylene within the mill, discharge means for the mill, and a liquid seal on the discharge means from said mill.
13. The combination with a classifier, of means to enclose said classifier so as to prevent the escape of gases therefrom; a substantially gas-tight grinding mill in closed circuit, with said classifier, means for feeding material to said circuit, a substantially gas-tight enclosure at the feed end of said mill, means for raising material within said enclosure, feeding the same to said mill, and means for feeding the coarse material discharged from said classifier into said enclosure.
14. The combination with a classifier, of means to enclose said classifier so as to prevent the escape of gases therefrom, a substantially gas-tight grinding mill in closed circuit with said classifier, means for feeding crushed wet ore into said mill, means for maintaining acetylene in said mill, means for supplying water to the mill, means for discharging the material from said mill below the water level in said classifier, and means for recycling at least a portion of the water containing absorbed acetylene, through the mill.
15. The combination with a substantially gas-tight enclosure, of a screw for feeding material thereinto, a short substantially straight passage between said screw and enclosure, means for supplying crushed ore to said screw, and means for supplying water to the screw.
16. The combination with a substantially gas-tight enclosure, of a screw for feeding material thereinto, a short substantially straight passage between said screw and enclosure, and having a tapered constriction therein for compacting the material.
17. The combination with a substantially gas-tight enclosure, of a screw for feeding material thereinto, a short substantially straight passage between said screw and enclosure, and an agitator to break up the material at the discharge end of said passage.
18. An ore filming device which comprises a gas-tight enclosure which includes a mill capable of grinding ore in the presence of a film-producing gas, a passage to introduce ore into said enclosure, means in said passage to form a seal at the feed-end of said enclosure, gas-tight means to separate ore discharged from said mill, and a gas-tight connection on said mill and separator for discharging the contents of said mill and for conducting the same to the separator.
19. An ore filming device comprising a gas-tight enclosure for grinding ore in the presence of a film-producing gas, feeding means to introduce ore into said enclosure, means to form a seal in said feeding means, a gas-tight means to separate coarse aggregates of ore and to return the same to the feeding means, and means to separate gas-charged water from the ground ore and to return at least a part of said water to the feeding means.
20. The combination with a classifier having means to discharge finely ground ore and means to discharge coarse aggregates of ore, of means to enclose said classifier so as to retain gases therein, a feed pipe for said classifier, an air-tight enclosure including a grinding mill and a chamber, the discharge of said mill being connected with the feed pipe of said classifier, scoop means in said chamber to feed ore to said mill, and means between the discharge for coarse aggregates and the chamber to form a plug of ore and continuously advance the same into the chamber.
- In testimony whereof, I affix my signature.
- JOHN M. CALLOW.
